INTERNAL SHIELD FOR VAPOR ELECTRIC
DEVICESHarold Winograd, Milwaukee, Wis., assignor to
Allis-Chalmers Manufacturing Company, Mil-
waukee, Wis., a corporation of Delaware

Application October 18, 1948, Serial No. 55,204

11 Claims. (Cl. 250—27.5)

1

This invention relates in general to improvements in electric valves, and in particular to means for controlling faults in an electric valve using a vaporizable conducting medium, and is especially useful in connection with electric valves of the single anode type.

Electric valves are rated according to the current which they will deliver to a load circuit. A limiting factor in the current rating is the frequency of occurrence of faults such as arc-backs and stray arcs. An arc-back may be defined as a flow of current in a reverse direction through the valve, due to the formation of a cathode spot on the anode, and results in a failure of the rectifying action of the valve. A stray arc may be defined as a flow of current in the forward direction through the valve from the anode to the casing, and results in erosion of the casing.

In electric valves of the type in which the cathode is not insulated from the casing, stray arcs are created when the cathode spot is transferred from the cathode to the casing. Arc-backs occur in the same type of valve for reasons not clearly known, and may result in a current flow from the casing to the anode. Since these operating faults are more likely to occur at elevated temperatures and high vapor pressures, it has been customary to provide cooling means for maintaining the valve temperature and vapor pressure within specified limits.

One form of cooling means heretofore used in the non-insulated cathode type of valve, comprises a cooling coil of small uniform pitch insulated from the casing and disposed within the casing surrounding the arc region. When so placed adjacent the arc region, the cooling coil carries off heat transmitted to it from the anode and the arc by radiation, as well as heat transferred to it by condensation of the vaporizable cathode medium on the surface of the coil. The cooling coils used heretofore have been so wound that adjacent turns define a uniformly narrow gap which is relatively pervious to the flow of the vaporizable medium, but which is substantially impervious to the formation of arcs between the anode and the casing wall.

The condensing action of the cooling coil is a function of the surface presented to the vapor, the rate of flow of the vapor over that surface, and the quantity and temperature of cooling fluid passed through the coil. However, with a fixed surface area, a fixed rate of vapor flow, and a fixed temperature of cooling fluid, a saturation point is reached at which an increase in the flow of cooling fluid through the coil produces no ap-

2

preciable increase in condensate. It is therefore desirable in the design of a cooling coil to present a condensing surface of maximum area in the region of the highest vapor pressure and rate of flow.

In a coil having a pitch defining a uniformly narrow gap between adjacent turns, the rate of flow of the vaporizable medium between adjacent turns is limited by the gap width. The portion of the coil surface which faces inward toward the arc region lies in a zone of relatively high vapor pressure and unrestricted vapor flow, and is fully effective in condensing the vapor present and returning it to the cathode. The balance of the coil surface which is not directly exposed to the arc region is much less effective in condensing vapor from the region of relatively high vapor pressure, because of the restricted gap through which the vaporizable medium must flow to reach the balance of the coil surface. If the coil is rewound with a greater pitch defining a larger gap through which the vaporizable medium may flow unrestricted, then the coil is no longer impervious to stray arcs, or to flow of arc-back currents from the casing.

Since the gap between adjacent turns is critical in an arc-impervious coil it has heretofore been necessary to construct the coil with a uniform gap width, not exceeding specified maximum and minimum tolerances. This construction necessitates the introduction of spacers between turns and calls for a tolerance of manufacture far beyond that required in the present invention, in which the cooling coil is wound with any width of gap, above a predetermined minimum value.

The present invention proposes to shield the casing from the arc region to prevent the formation of stray arcs and at the same time provide for an optimum rate of heat transfer from the vaporizable medium to the cooling means, whereby the cooling means may effectively act as a surface condenser to maintain a suitable vapor pressure in the valve. The present invention also proposes to shield the casing of the valve to prevent the casing from participating as an electrode in the flow of fault current to the anode during an arc-back.

A barrier extending from the anode to the cathode coextensive with the cooling coil is disposed between the cooling coil and the casing to provide this shielding without interfering with the cooling and condensing function of the coil. Such a barrier, by confining an arc-back to the space between the anode and the cathode, is instrumental in restricting the arc path. As a con-

sequence, the arc-drop voltage is increased with a resulting lower value of fault current through the valve.

It is therefore an object of the present invention to provide an electric valve of the vaporizable cathode type in which the aforementioned disadvantages of the prior art are obviated, and in which the aforementioned advantages are achieved.

Another object of the present invention is to provide an improved electric valve of the non-insulated cathode type in which it is unnecessary to wind the cooling coil with a uniform pitch.

Another object of the invention is to provide an improved electric valve of the vaporizable cathode type in which the arc region between the anode and the cathode is shielded against stray arcs and at the same time effectively cooled through the unrestricted transfer of heat to the cooling means.

Another object of the invention is to provide an electric valve of the vaporizable cathode type in which the cooling means provides for unrestricted flow therethrough of the vaporizable medium of the valve for the condition of optimum heat transfer between the medium and the cooling means.

Another object of the invention is to provide an electric valve of the vaporizable cathode type in which the cooling means provides a substantially unrestricted surface area for the condensation thereon of the vaporizable medium of the valve.

Another object of the invention is to provide an improved electric valve of the vaporizable cathode type, in which the casing of the valve is prevented from participating as an anode in the flow of current during an arc-back.

Another object of the invention is to provide an improved electric valve of the vaporizable cathode type in which the casing of the valve is shielded against the formation of stray arcs between the casing and the anode.

Another object of the invention is to provide an electric valve of the vaporizable cathode type in which arc-backs are confined to the arc region between the anode and the cathode.

Another object of the invention is to provide an electric valve in which restricting the path of the arc-back current is instrumental in reducing the fault current flowing through the valve.

Another object of the invention is to provide an electric valve in which the cooling means is simpler to construct, cheaper to manufacture, and is more efficient in operation.

The novel features of the invention and how the objects are obtained will be apparent from this specification and the accompanying drawings showing several embodiments of the invention and forming part of this specification and all the novel features are intended to be pointed out in the appended claims.

Fig. 1 is a vertical section through a sealed electric valve of the single anode type in which a shield embodying the invention is shown surrounding the arc region;

Fig. 2 is a fragmentary vertical section through a similar valve in which the shield is mechanically supported by the cooling coil;

Fig. 3 is a fragmentary view, partly in elevation and partly in section, of an alternate embodiment of the shield shown in Fig. 1;

Fig. 4 is a fragmentary horizontal section showing the electrical header of the anode baffle disposed between adjacent parts of the shield;

Fig. 5 is a vertical section through one of the risers of the cooling coil showing the fluid-tight seal between the riser and the casing of the valve.

The invention lends itself to embodiment in any well known type of valve with single or plural anodes, but for purposes of exemplification the invention is shown in Fig. 1 embodied in an electric valve 11 of the single anode type. The electric valve here shown comprises a substantially cylindrical cup-shaped casing 12 which is preferably made in whole or in part of a conducting material, such as steel. The casing is closed at its open end by a disk-shaped anode plate or cover 13, the plate 13 being dished upward at its outer rim to form a lip following the inner peripheral contour of the casing 12. The anode plate 13 is preferably made of steel and is sealed in fluid-tight relation to the casing 12 by any suitable means, as by welding the lip of the plate 13 to the casing 12.

The anode plate 13 carries a main anode 14 which depends therefrom into the casing 12. The anode 14 is electrically connected to a cylindrical conducting shaft 15 mounted within an insulating sleeve 16 extending upward through the anode plate 13. Means for sealing the shaft 15 against the anode plate 13 comprises a laminated vitreous seal 17, which, in addition to providing a fluid-tight seal, also electrically insulates the shaft 15 from the anode plate 13 and provides the shaft 15 with the necessary mechanical support. As shown, the shaft 15 threads into a tapped axial bore in the anode 14. A portion of the shaft 15 extending above the anode plate 13 is fitted with a cooling radiator 18 for dissipating heat from the anode 14 during operation of the valve 11. The anode 14 is generally cylindrical in shape and preferably made of a conductive material such as graphite.

The electric valve 11 is provided with a cathode 19 comprising a pool of mercury or other suitable vaporizable material in electrical contact with the casing 12. An upward-extending annular insulator 21, known as a cathode ring and preferably made of a material such as quartz, bounds the active surface of the mercury. The cathode ring 21 is coaxially mounted in any suitable manner on a radially notched disk 22 which in turn is carried by the bottom of the casing 12.

A control electrode or grid 23 is arranged in spaced proximity to the anode 14 for controlling the flow of current between the anode 14 and the cathode 19. The grid 23 is preferably made of a conductive material such as graphite, and is desirably basket-shaped to follow the contour of the anode 14. Numerous perforations are provided in the side and bottom walls of the grid 23 to permit the passage of the arc discharge between anode 14 and cathode 19 and to permit the radiation therethrough of heat from the surface of the anode 14 during operation of the valve 11. The grid 23 is preferably supported from the anode plate 13 by a plurality of depending segmental insulators 24, only one of which is shown. A control potential may be impressed upon the grid 23 through an electrically insulated fluid-tight connection, not shown, penetrating the anode plate 13.

The paths of the arc discharge between anode 14 and cathode 19 and of the flow of material vaporized from the cathode 19 during operation of the valve are controlled by means of a disk-shaped baffle 25 axially disposed below the grid 23, and by means of cooling means and shielding means, hereinafter described.

The baffle 25 is preferably made of a conductive material such as graphite. The cooling means comprises a cooling coil 26 which encircles the arc region and extends below the disk-shaped baffle 25. The cooling coil 26 is preferably made of stainless steel which prevents free hydrogen from passing through the pipe wall from the cooling fluid to the interior of the casing.

The coil 26 is preferably constructed of pipe of circular cross section, forming a passage for the flow of water or other cooling fluid. It may be wound as a single helix, or it may be wound as two helixes interleaved with one another and joined by a common connection. Assuming that the coil 26 is wound as a single helix, the pitch is so chosen that the gap defined by adjacent turns has any width above a predetermined minimum value so as to permit an unimpeded flow of mercury vapor across the turns. The selection of a predetermined minimum gap width is an empirical one since it is mathematically infeasible to make such a determination. Theoretically a straight pipe axially disposed within the casing would offer the least resistance to vapor flow but such a pipe would lack the condensing surface required. A balance therefore is struck between the amount of condensing surface required and a gap which will permit substantially unimpeded flow of the vapor. Since the maximum clearance is not critical, no spacers are required between turns to hold the gap to a maximum width.

The free ends of the coil 26 terminate in upward-extending risers 27 for leading the coil 26 through the anode plate 13. The risers 27 penetrate the anode plate 13 diametrically and are respectively sealed thereagainst by means of a flexible composite vitreous seal 28, as shown in Fig. 5. If desired, the risers may be provided with insulating means, such as insulating sleeves, not shown. In addition to sealing the risers 27 in fluid-tight relation against the anode plate 13, the seals 28 electrically insulate the coil 26 from the anode plate 13 and the casing 12. Protection against breaking the seals 28 is afforded by upward-extending sleeves 29 mounted in any suitable manner on the anode plate 13. An annular insulator 31 closes each sleeve and electrically insulates the risers 27 therefrom. An annular gland 32 cooperates with the insulator 31 to hold the insulator 31 against the riser 27. Attached to the upper end of each riser is an elbow fitting 33 having a flange 34 for connection to a source of cooling fluid, not shown.

Referring to Fig. 1 it will be observed that the lower end of the cooling coil 26 supports the disk-shaped baffle 25. In turn the baffle supports an excitation anode 35 insulated therefrom. A suitable potential may be impressed on the anode 35 through an insulated lead-in 36. Below the cathode 19, a starting device 37, preferably of the electro-magnetic type, momentarily connects the cathode pool 19 with the excitation anode 35 when it is desired to ignite an arc at the cathode 19 to place the valve 11 in service.

The shielding means comprises a cylindrical shield 38, preferably made of metal such as steel, but which may be made of an insulating material, such as porcelain. The shield 38 encloses the coil 26 and extends substantially coaxially therewith from the region of the anode 14 to the cathode ring 21. In this manner the shield 38 surrounds the arc region between the anode 14 and the cathode 19.

The shield 38 is suspended from the anode plate 13 by a plurality of insulators 39 depending there-

from. An upper closure for the shield is provided by a disk-shaped cover 40 having a depending rim 41, the cover 40 being supported from the anode plate 13 by the segmental insulators 39. The shield 38 may be fastened to the cover 40 in any suitable manner, as by welding, as shown in Fig. 1, or as by screws 43 penetrating the rim 41 of the cover 40, as shown in Fig. 2. In the connection shown in Fig. 2, the shield 38 is separable from the cover 40 for ready access to those elements of the valve 11 concealed within the shield 38.

At its lower end, the shield 38 converges toward the cathode 19 to form a funnel 44 integral with the shield 38. Although the funnel 44 is here shown integral with the shield 38, the funnel 44 may be constructed as a separate element and fastened to the bottom of the shield 38 in any suitable manner. It will be observed that the funnel 44 opens into the space above the cathode 19 enclosed by the cathode ring 21. Thus positioned, the funnel 44 acts as a collector for catching mercury condensed by the coil 26 and returning it to the cathode 19.

The shield 38 is axially notched as shown in Fig. 4 to incorporate the insulated lead-in 36 of the excitation anode 35 within the curved surface of the shield 38.

Referring to Fig. 1, it will be noted that the cooling coil 26 rests on a series of annularly-disposed metal pads 45 supported by the funnel 44. An electrical connection is thus made between the shield 38 and the cooling coil 26 at the lower end thereof. In this way, the coil 26 and shield 38 are maintained at the same electrical potential with respect to one another. Since both the coil 26 and the shield 38 are electrically insulated from the anode plate 13, they are also insulated from the casing 12. In operation of the valve 11, the coil 26 and shield 38 have a floating potential with respect to the cathode 19 which, as hereinbefore disclosed, is directly connected to the casing 12. Although the shield 38 is electrically connected to one end of the coil 26 through the pads 45, it is spaced sufficiently from the coil 26 throughout its axial length to permit the free flow of mercury vapor around the turns of the coil 26 during operation of the valve 11.

As shown in Fig. 2, an alternative method of supporting the shield 38 comprises hanging it on the risers 27 of the coil 26 by means of clamps 46 which bolt to the shield 38 and securely grip the outer surface of the risers 27. When supported in this manner, the shield 38 does not require the support furnished by the insulators 39 of Fig. 1. If the cooling coil 38 is to be utilized as a resistance heater during forming of the valve 11, as described in Patent No. 2,459,057, to Harold Winograd, then the construction of Fig. 1 is preferred, because the heating current may be passed through the coil 26 without being shunted by the shield 38. The clearances between the shield 38 and each of the following elements, the anode shaft 15, risers 27, lead-in 36, and cathode ring 21, while sufficient to provide a gap therebetween for insulating and degassing purposes, are substantially impervious to the passage of stray arcs therethrough. It will thus be noted that the shield 38 together with the cover 40 provides an arc-impervious barrier surrounding the arc region of the valve 11. How the shield 38 operates to prevent stray arcs is described as follows.

Prior to placing the valve 11 in operation, the valve is formed or degassed by evacuating the

casing 12 and applying heat to drive out the occluded gasses. One method of forming the valve 11 is described in Patent No. 2,459,057 to Harold Winograd. Following degassing of the valve 11, the casing 12 is sealed off and the valve 11 operated as a hermetically sealed unit.

In operation, the valve 11 is started by energizing the starting device 37 and striking an arc between the excitation anode 35 and the cathode 19. A cathode spot is thus established and the cathode 19 remains continuously emissive. If a load circuit is now connected to the valve 11 and the grid voltage properly adjusted to make the valve 11 conductive, an arc will be formed between the anode 14 and cathode 19 through the mercury vapor contained in the valve 11. The arc passes through the apertures of the grid 23 and follows a path defined by the baffle 25 and shield 38. The flow of current raises the anode temperature, the temperature rise being a function of the current intensity. However, the heat radiated by the anode 14 is absorbed in the cooling coil 26, the perforations in the grid 23 allowing the anode 14 to radiate directly to the coil 26. In addition, the coil 26 absorbs heat radiated by the arc between the anode 14 and the cathode 19. A flow of water or other cooling fluid through the coil 26 absorbs the heat radiated to the coil.

Concomitant with the radiation of heat to the cooling coil 26, is the transfer of heat to the cooling coil 26 by the condensation of mercury vapor on the surface of the coil. During operation of the valve 11 there is a constant flow of mercury vapor throughout the casing 12 and over the turns of the coil 26. The pitch of the coil 26 is selected to facilitate this flow between turns. In the absence of a shield, such as the shield 38, the mercury arc, at high current loads, might sometimes transfer from the cathode 19 to the casing 12, forming a cathode spot on the casing wall. In such a case, since the gap between adjacent turns of the cooling coil 26 is not impervious to the passage of an arc between turns, the cooling coil 26 alone would offer no barrier to the formation of stray arcs. By placing a shield such as the shield 38 here shown, between the coil 26 and the casing 12, the passage of stray arcs between turns is effectively blocked. The shield 38 therefore forms a substantially perfect barrier against the formation of an arc between the anode 14 and the casing 12, and yet permits the mercury vapor to flow freely over the turns of the cooling coil 26.

By combining the shield 38 with the cooling coil 26, the optimum utilization of the coil 26 as a surface condenser is effected and the casing 12 of the valve 11 protected from the erosive action of stray arcs.

An alternative form of shield is shown in Fig. 3, in which the wall 47 of the shield is perforated throughout its axial length. It has been found that numerous small perforations in the shield 47 permit easier removal of the gases liberated during the degassing process without rendering the shield pervious to arc discharge during operation of the valve. For a like reason a perforated shield, such as the shield 47, is preferred for use in a valve which is continuously connected to an evacuating means during operation.

Although but three embodiments of the present invention have been herein illustrated and described, and although these embodiments have been described particularly in connection with electric valves of the single anode type, it will be apparent to one skilled in the art that the inven-

tion may have desirable functional utility in other types of electric valves. And it should be understood that the invention of the appended claims is not limited to the exact details of design and construction described herein, for obvious changes and modifications within the scope of the claims will be apparent to those skilled in the art.

It is claimed and desired to secure by Letters Patent:

10. An electric valve comprising in combination an evacuated casing, a plurality of cooperating electrodes including an anode and a cathode disposed within said casing, cooling means for cooling said valve disposed within said casing adjacent to said electrodes, said cooling means being insulated from said casing, and shielding means interposed between said cooling means and said casing adjacent to said cooling means and extending from said anode to said cathode, said shielding means being impervious to arc formation between said anode and said casing.
15. In an electric valve, the combination of an evacuated casing comprising a pool of vaporizable conductive material serving as a cathode disposed in said casing in conductive relation thereto; an anode disposed in said casing in insulated relation thereto; cooling and condensing means comprising a coil forming a passage for the flow of cooling fluid therethrough, said coil having spaced turns defining a gap therebetween pervious to the unrestricted flow of material vaporized from said cathode pool to enable said vaporized material to have access to all surfaces of said member to condense thereon, said coil being insulated from said anode and said casing; and shielding means comprising a cup-shaped envelope coextensive with said coil disposed between said coil and said casing to form an arc impervious barrier between said anode and said casing.
20. In an electric valve employing a vaporizable cathode to provide an ionizable medium for the conduction of an arc therethrough, cooling means pervious to the flow of the ionizable medium disposed adjacent said arc for cooling said arc and returning said ionizable medium to said cathode, and a cylindrical arc impervious shield disposed within said valve jacketing said cooling means, said shield cooperating with said cooling means to confine said arc to said cathode.
25. An electric valve comprising in combination an evacuated casing, a plurality of cooperating electrodes including an anode and a cathode disposed within said casing, cooling means for cooling said valve disposed within said casing adjacent to said electrodes, and shielding means interposed between said cooling means and said casing and extending from said anode to said cathode and insulated from said casing for preventing arc formation between said anode and said casing.
30. An electric valve comprising in combination an evacuated casing, a plurality of cooperating electrodes including an anode and a cathode disposed within said casing, cooling means for cooling said valve disposed within said casing adjacent to said electrodes, and shielding means comprising a cylindrical envelope substantially closed at one end thereof interposed between said cooling means and said casing and extending from said anode to said cathode and insulated from said casing for preventing arc formation between said anode and said casing.
35. In an electric valve: the combination of an evacuated casing comprising a pool of vaporizable conductive material serving as a cathode dis-

posed in said casing in conductive relation thereto; an anode disposed in said casing in insulated relation thereto; and means for preventing arcing between said anode and said casing comprising in combination a member forming a passage for the flow of cooling fluid therethrough, said member being pervious to the unrestricted flow of material vaporized from said cathode pool to enable said vaporized material to have access to all surfaces of said member to condense thereon, and a shield coextensive with said member disposed between said member and said casing to form with said member an arc impervious barrier between said anode and said casing.

7. An electric valve comprising in combination an evacuated casing, a plurality of co-operating electrodes including an anode and a pool of vaporizable material serving as a cathode disposed within said casing in conductive relation thereto, cooling means for cooling said valve disposed within said casing adjacent to said electrodes, and shielding means comprising a perforated cylindrical envelope substantially closed at one end thereof interposed between said cooling means and said casing and extending from said anode to said cathode and insulated from said casing, said envelope being pervious to the flow of said material therethrough and impervious to arc formation between said anode and said casing.

8. Means for preventing the formation of cathode spots on the casing of an electric valve having a plurality of electrodes comprising an arc impervious shield disposed within said casing in spaced relation thereto, said shield substantially enclosing said electrodes; cooling means disposed within said shield and spaced therefrom for cooling said electrodes; and insulating means disposed within said casing for insulating said shield from said casing.

9. In an electric valve of the single anode type having an evacuated casing, and a vaporizable cathode electrically connected to said casing, the combination of cooling means for cooling said

5
10

valve disposed within said casing, said cooling means comprising a coil having spaced turns extending from said anode to said cathode and insulated therefrom, and shielding means comprising an arc-impervious element interposed between said coil and said casing and insulated from said casing, said arc-impervious element extending coextensively with said coil to prevent the passage of stray arcs through the turns of said coil.

10. An electric valve comprising an evacuated casing, an anode disposed within said casing, a vaporizable cathode within said casing providing an ionizable medium for arc conduction between said anode and said cathode, a control electrode adjacent said anode for controlling the initiation of said arc, cooling means adjacent said control electrode for cooling said arc, and arc impervious shielding means between said cooling means and said casing for confining said arc to said cathode and said anode.

11. In an electric valve: the combination of an evacuated casing comprising a pool of vaporizable conducting material serving as a cathode disposed in said casing in conductive relation thereto; an anode disposed in said casing in insulated relation thereto; and means insulated from said anode and said casing for preventing arcing between said anode and said casing comprising in combination a member forming a passage for the flow of cooling fluid therethrough; said member being pervious to the unrestricted flow of material vaporized from said cathode pool to enable said vaporized material to have access to all surfaces of said member to condense thereon, and a shield coextensive with said member and connected thereto disposed between said member and said casing to form with said member an arc impervious barrier between said anode and said casing.

HAROLD WINOGRAD.
